AUTOMATIC LOCK FOR DISPENSING MACHINE

Emery Mihalek and Charles Szyper, Chicago, Ill., assignors to Hershey Mfg. Co., Chicago, Ill., a corporation of Illinois

Application September 15, 1955, Serial No. 534,523

3 Claims. (Cl. 221—206)

This invention relates to dispensing machines and particularly to a device for automatically locking such a machine after a dispensing operation so as to prevent operation of the machine by spurious means.

The present invention comprises improvements which are applicable to machines of the type disclosed in the following United States patents: 1,562,771, 1,586,455, 1,570,910, 1,677,647, 1,697,537, 1,706,896, 1,798,416, 1,923,945, and 2,477,137.

Thus, one principal object of the invention is to provide a new and improved dispensing machine having a locking device for locking the machine, after each dispensing operation, so as to prevent operation of the machine by means of a spurious implement or the like.

A further object is to provide a new and improved dispensing machine having a movable dispensing member for carrying objects from a magazine to a discharge opening, together with a locking device for locking the dispensing member in its dispensing position, adjacent the discharge opening, so as to prevent movement of the dispensing member by a spurious implement inserted through the discharge opening.

It is another object to provide a new and improved dispensing machine of the foregoing character in which the locking device is automatically released by initial operation of the actuating element normally employed to operate the dispensing member.

Further objects and advantages of the machine will appear from the following description, taken with the accompanying drawings, in which:

Figure 1 is a fragmentary elevational sectional view of a dispensing machine constituting an illustrative embodiment of the invention, the view being taken generally along a line 1—1 in Fig. 7;

Figs. 2 and 3 are views similar to Fig. 1 with the machine in changed positions, the machine being shown in its initial position in Fig. 1, in its locked position in Fig. 2, and in an unlocked and partially reset position in Fig. 3;

Fig. 4 is a fragmentary elevational sectional view taken generally along a line 4—4 in Fig. 1;

Fig. 5 is a fragmentary rear elevational view of the machine;

Fig. 6 is a fragmentary side elevational view of the machine;

Fig. 7 is a horizontal sectional view taken generally along a line 7—7 in Fig. 1, the machine being shown in its initial position; and

Fig. 8 is a view similar to Fig. 7, with the machine in changed position.

It will be seen that the drawings illustrate a dispensing machine 10 having a magazine 12 (Figs. 2—4) adapted to hold a supply of articles to be dispensed. As illustrated, the magazine is in the form of a generally vertical tube adapted to hold a stack of the articles. To discharge the articles, a circular opening 14 is formed in a horizontal base plate 16. It will be seen that the opening 14 is displaced rearwardly from the magazine 12.

To carry the articles from the magazine 12 to the dis-

2

charge opening 14, the machine is equipped with a plurality of movable slides or other dispensing members arranged in vertically superimposed relation. In this instance, there are five dispensing slides 18, 19, 20, 21 and

22. Each of the slides 18—22 is biased rearwardly by means of a spring 24. Above and below the slides 18—22 are apertured upper and lower gates 26 and 27. However, the construction and function of these gates 26 and 27 are not material to the present invention and hence need not be described in detail. The dispensing slides 18—22 have respective vertical apertures 28—32 adapted to receive articles from the magazine 12 and carry them to the discharge opening 14. In the initial position of the machine, as shown in Fig. 1, all of the apertures 28—32 are aligned with the magazine 12. Accordingly, the articles will descend by gravity from the magazine into the apertures. The dispensing operation is accomplished by moving one or more of the slides rearwardly so that the apertures in the slides will be aligned with the discharge opening 14, whereupon the articles contained in the apertures will fall through the discharge opening.

To actuate the dispensing slides 18—22, the machine is provided with an actuating lever or other member 34 (Fig. 6), which is mounted on a pivot shaft 36 supported by a right hand side frame 38. The lever 34 is adapted to operate a trip lever 40 by means of an escapement 42.

It will be seen that the trip lever 40 has a shaft portion 44 (Fig. 5) provided with right and left hand journals 46 and 48 which are mounted in bearings 50 and 52. Extending forwardly on the trip lever 40 is a pointed escapement arm 54 which is normally engaged by a pawl 56 carried by the actuating lever 34. When the actuating lever 34 is swung manually in a counterclockwise direction, as seen in Fig. 6, the pawl 56 lifts the arm 54 so as to swing the trip lever 40 clockwise. After a predetermined amount of movement of the actuating lever 34, the arm 54 escapes from the pawl 56 and returns in a counterclockwise direction under the biasing impetus of a spring 58. The actuating lever 34 must be returned manually in a clockwise direction. To prevent premature return of the lever 34, a two-way pawl 60 is arranged to engage a segmental ratchet 62 on the lever 34.

The initial, clockwise swinging movement of the trip lever 40 is effective to reset the dispensing slides 18—22 into their article-receiving positions in vertical alignment with the magazine 12. Such resetting action is brought about by means of a depending arm 64 (Fig. 1) on the lever 40. It will be seen that a link 66 is connected between the arm 64 and a push pin 68 which is slidably guided in an upright projection 70 formed on the base plate 16. The pin 68 is adapted to engage an upright flange member or finger 72 formed on the rear end of the lowermost dispensing slide 18. This finger 72 extends upwardly along the rear ends of the other dispensing slides 19—22 and hence is adapted to push the slides forwardly. The clockwise initial movement of the trip lever 40 advances the pin 68. As shown to best advantage in Fig. 3, the pin 68 engages the finger 72, which in turn engages any of the slides 19—22 which have been moved to dispensing positions. The finger 72 pushes the slides forwardly into their article-receiving positions.

When the dispensing slides 18—22 reach their fully advanced, article-receiving positions underneath the magazine 12, they are latched by means of a latching arm 74 (Figs. 7 and 8), which swings behind the finger 72 on the lowermost slide 18. It will be seen that the arm 74 is formed on a horizontal latching lever 76 which is biased counterclockwise by a spring 78. Thus the spring is effective to swing the arm 74 into its latching position.

A horizontal arm 80 is provided to swing the latching lever 76 clockwise and thereby disengage the latching arm 74 from the finger 72 on the lower most dispensing slide

18. In this way, the dispensing slides 18-22 are conditioned for rearward movement between their article-receiving and article-dispensing positions. During the clockwise initial movement of the trip lever 40, the horizontal lever 80 is swung forwardly so as to permit the latching arm 74 to move behind the finger 72. Such forward movement of the lever 80 is effected by means of a link 82 which is connected between the lever 80 and a second horizontal lever 84. To actuate the lever 84, the trip lever 40 is provided with a second depending arm 86 10 which is engageable with an eccentric roller 88 mounted on the lever 84. Initial clockwise movement of the trip lever 40 swings the depending arm 86 in a forward direction so that it engages the roller 88 and thereby swings the levers 84 and 80 forwardly. Upon return movement of the trip lever 40, the depending arm 86 moves away from the roller 88 to permit return of the lever 84 under the impetus of a biasing spring 90.

Return movement of the lever 84 is retarded by means of a suitable retarding mechanism 92 (Figs. 5, 7 and 8). The illustrated retarding mechanism 92 is of the air fan type. Thus, a two-armed fan 94 is arranged to be driven at high speed by the lever 84 during its return movement. During return movement of the lever 84, a one-way ratchet clutch 96 (Fig. 5) connects the lever to a gear 98 which drives the fan 94 through a conventional speed-multiplying gear train 100 (not completely shown). The air resistance offered to rotation of the fan 94 retards the return movement of the levers 84 and 80. Near its rearward limit of travel, the lever 80 engages an upstanding projection 102 on the latching lever 76 and thereby swings the latching lever in a clockwise direction so as to disengage the arm 74 from the finger 72 on the lowermost dispensing slide 18.

After the slides 18-22 have been released by the master latching arm 74, the rearward movement of the slides is controlled by means of a suitable selector mechanism 104 (Fig. 1) which, however, is not material to the present invention and hence need not be described in detail. The selector mechanism operates in such manner that it 40 may release one or more of the slides for rearward movement into dispensing position. Due to the provision of the finger 72, the lowermost slide 18 must be released for rearward movement before any of the other slides 19-22 can travel rearwardly.

It will suffice to note that the selector mechanism 104 comprises a plurality of individual latches 106 (Figs. 6 and 7), one latch being provided for each of the slides 18-22. The selector mechanism is arranged to release the latches 106 in various combinations during the return movement of the lever 80. When the master latching arm 74 is released, as shown in Fig. 7, those slides for which the individual latches 106 are also released will travel rearwardly under the impetus of the biasing springs 24. When the slides are reset forwardly by the push pin 68, the latches 106 are returned into latching position by means of individual biasing springs 108.

Fig. 2 illustrates one possible dispensing position of the machine in which the three lower dispensing slides 18, 19 and 20 are shifted rearwardly so that the apertures 28, 29 and 30 therein are in overlying relation to the discharge opening 14. With the slides 18, 19 and 20 in this position, the articles carried in the apertures will be dispensed through the opening 14.

It has been found desirable to prevent spurious operation of the dispensing machine. Such spurious operation has sometimes been accomplished by the insertion of a tool or implement through the discharge opening 14 by an unauthorized person. The implement has then been manipulated so as to reciprocate the lowermost slide 18 between its article-receiving and dispensing positions. This is done when only the lowermost slide has been released to its dispensing position. By such reciprocation of the lowermost slide, the entire contents of the magazine 12 might conceivably be removed.

In accordance with the present invention, such spurious operation of the lowermost dispensing slide 18 is prevented by means of an automatic locking device 110 which retains the lowermost slide in its dispensing position, once it has been moved to this position by legitimate operation of the machine. It will be seen from Figs. 1-3, that the locking device 110 comprises a locking pawl or latch 112 connected by means of a pivot 114 to a bracket 116 which in turn is mounted on an arm 118 extending forwardly on the trip lever 40. The pawl 112 has a limited range of free swinging movement relative to the arm 118. This range of free movement, or lost motion, is defined by an arcuate slot 120 formed in the pawl 112. The bracket 116 carries a headed pin 122 which extends through the slot 120 and limits the movement of the pawl 112.

It will be seen that the pawl 112 is formed with a depending tooth 124 which defines a rearwardly facing latching shoulder 126. An inclined cam surface 128 is formed along the front of the pawl 112 and is arranged to face downwardly and forwardly. When the lowermost dispensing slide travels rearwardly to its dispensing position, the finger 72 engages the cam surface 128 so as to displace the pawl 112 upwardly. Thus, the pawl 112 offers no resistance to rearward movement of the slides 18-22. Once the lowermost slide 18 has reached its dispensing position at the rearmost limit of its travel, the pawl 112 moves downwardly, under the biasing action of gravity, with the tooth 124 and latching shoulder 126 in front of the finger 72. It is then impossible to move the lowermost dispensing slide 18 in a forward direction until the pawl 112 is released.

The pawl 112 is automatically released by actuation of the machine in the normal manner. Thus, initial clockwise actuating movement of the trip lever 40 swings the arm 118 upwardly. This raises the pawl 112 so that the latching shoulder 126 will be disengaged from the finger 72. Such releasing movement of the pawl 112 occurs before the push pin 68 engages the finger 72.

In normal operation, the machine is actuated by pushing the front end of the actuating lever 34 downwardly so as to move the lever counterclockwise. The pawl 56 on the lever 34 raises the trip arm 54 until the arm escapes from the pawl. The raising movement of the arm 54 results in clockwise actuation of the trip lever 40. When the arm 54 escapes from the pawl 56, the biasing spring 58 returns the lever 40 in a counterclockwise direction.

During clockwise actuation of the trip lever 40, the arm 118 disengages the locking pawl 112 from the finger 72, assuming that the lowermost dispensing slide has been moved rearwardly during previous operation of the machine. After the pawl 112 has been released from the finger 72, the arm 64 actuates the push pin 68 so as to reset the lowermost slide 18 forwardly. The finger 72 on the lowermost slide resets any of the other slides 19-22 which may previously have been moved rearwardly.

During clockwise actuation of the trip lever 40, the depending arm 86 on the lever engages the roller 88 and operates to swing the lever 84 and 80 forwardly. Such movement of the lever 80 releases the master latching lever 76 so that the latching arm 74 can move behind the finger 72 when the lowermost slide 18 reaches its forwardly reset position. The latching arm 74 temporarily retains the dispensing slides 18-22 in this position, with their apertures 28-32 underneath the magazine 12. The articles held in the magazine thereupon fall into the apertures in the slides.

When the trip lever 40 returns to its original position, the locking pawl 112 is moved downwardly into the path of the finger 72 on the lowermost dispensing slide 18. Moreover, the levers 80 and 84 are released for rearward movement. However, the rearward movement of the levers is retarded by the air fan mechanism 92. During the retarded return movement of the lever 80, the selector mechanism 104 may release one or more

of the latches 106. Shortly before the lever 80 reaches its return position, it engages the abutment 102 on the master latching lever 76 and is effective to swing the latch arm 74 out of the path of the finger 72. Thereupon, the lowermost slide 18 is moved rearwardly by its biasing spring 24, assuming that the latch 106 for the lowermost slide has been released by the selector mechanism 104. As the slide 18 moves rearwardly, the finger 72 engages the camming surface 128 on the locking pawl 112 and displaces the pawl upwardly. When the lowermost dispensing slide 18 reaches its dispensing position, with the finger 72 against the abutment 70, the pawl falls in front of the finger 72 so that the latching shoulder 126 will prevent forward movement of the slide 18. The pawl 112 makes it impossible for the slide 18 to be moved forwardly by means of a spurious implement inserted through the discharge opening 14 by any unauthorized person.

The pawl 112 remains in locking engagement with the finger 72 until the machine is again operated in the legitimate manner by swinging the lever 34.

Various modifications, alternative constructions and equivalents may be employed without departing from the true spirit and scope of the invention, as exemplified in the foregoing description and defined in the following claims.

We claim:

1. In a dispensing machine, the combination comprising a plurality of dispensing slides arranged in superimposed relation, a magazine overlying said slides, each of said slides having an article-receiving aperture therein, means defining a discharge opening underlying said slides for receiving articles therefrom, each of said slides being movable from an article-receiving non-dispensing position with said aperture therein alined with said magazine and an article-dispensing position with said aperture therein alined with said discharge opening, means for selectively moving said slides to said article-dispensing position, one of said slides being lowermost and having an upright member thereon extending along the ends of the other of said slides for moving the other of said slides into said article-receiving position upon movement of said lowermost slide into article-receiving position, said upright member preventing movement of the other of said slides into dispensing position until said lowermost slide is moved into dispensing position, an arm swingable in a generally vertical direction adjacent said slides, link means forming a lost motion connection between said arm and said lowermost slide and operative to move said lowermost slide to article-receiving position in response to predetermined upward movement of said arm, a latching pawl pivotally mounted on said arm and engageable with said upright member for latching said lowermost slide in said dispensing position, said pawl having a cam surface engageable by said upright member for displacing said pawl and permitting passage of said lowermost slide to said dispensing position without interference from said pawl, said pawl having a latching shoulder engageable with said upright member upon movement of said lowermost slide to said dispensing position, operable means for swinging said arm upwardly and thereby withdrawing said pawl from said upright member to release said lowermost slide for movement by said link means to said article-receiving position.

2. In a dispensing machine, the combination comprising a plurality of dispensing slides arranged in superimposed relation, a magazine overlying said slides, each of said slides having an article-receiving aperture therein, means defining a discharge opening underlying said slides

for receiving articles therefrom, each of said slides being movable from an article-receiving non-dispensing position with said aperture therein alined with said magazine to an article-dispensing position with said aperture therein alined with said discharge opening, respective springs biasing said slides toward said article-dispensing position, respective latches for releasably latching said slides in said article-receiving position, one of said slides being lowermost and having an upright member thereon extending along the ends of the other of said slides for moving the other of said slides into said article-receiving position upon movement of said lowermost slide into article-receiving position, said upright member preventing movement of the other of said slides into dispensing position until said lowermost slide is moved into dispensing position, an arm swingable in a generally vertical direction adjacent said slides, link means forming a lost motion connection between said arm and said lowermost slide and operative to move said lowermost slide to article-receiving position in response to predetermined upward movement of said arm, a latching pawl pivotally mounted on said arm and engageable with said upright member for latching said lowermost slide in said dispensing position, said pawl having a cam surface engageable by said upright member for displacing said pawl and permitting passage of said lowermost slide to said dispensing position without interference from said pawl, said pawl having a latching shoulder engageable with said upright member upon movement of said lowermost slide to said dispensing position, and operable means for swinging said arm upwardly and thereby withdrawing said pawl from said upright member to release said lowermost slide for movement by said link means to said article-receiving position.

3. In a dispensing machine, the combination comprising a magazine for holding a supply of articles, means defining a discharge opening displaced from said magazine, a dispensing member for carrying articles between said magazine and said discharge opening, said dispensing member having an article-receiving aperture therein, said dispensing member being movable between an article-receiving position with said aperture alined with said magazine and an article-dispensing position with said aperture alined with said discharge opening, means for selectively moving said dispensing member to said article-dispensing position, an arm swingable in a generally vertical direction adjacent said dispensing member, linkage means forming a lost motion connection between said arm and said dispensing member and operative to move said dispensing member to article-receiving position in response to predetermined upward movement of said arm, a latching pawl pivotally mounted on said arm adjacent said dispensing member, a latching element on said dispensing member and engageable by said latching pawl for latching said dispensing member in said dispensing position to prevent spurious movement of said dispensing member to said article-receiving position, and operable means for swinging said arm upwardly and thereby withdrawing said pawl from said dispensing member to release said dispensing member for movement by said linkage means to said article-receiving position.
